US0D1106600S

(12) **United States Design Patent** (10) **Patent No.:** **US D1,106,600 S**
(45) **Date of Patent:** **** Dec. 16, 2025**

(54) **BIRD FEEDER**

(71) Applicant: **dongguanshiyuyizhinengke-jyouxiangongsi**, Guangdong (CN)

(72) Inventor: **Junwang Cai**, Guangdong (CN)

(73) Assignee: **dongguanshiyuyizhinengke-jyouxiangongsi**, Dongguan (CN)

(**) Term: **15 Years**

(21) Appl. No.: **29/988,215**

(22) Filed: **Jan. 30, 2025**

(51) LOC (15) Cl. **30-03**

(52) U.S. Cl.

USPC **D30/126**

(58) **Field of Classification Search**

USPC ..... (57) **CLAIM**

The ornamental design for a bird feeder as shown and described.

DESCRIPTION

FIG. 1 is a perspective view of a bird feeder showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the bird feeder and form no part of the claimed design.

1 Claim, 8 Drawing Sheets
